UNITED STATES PATENT OFFICE.

CHARLES W. POWELL, OF GREEN ISLAND, NEW YORK.

BRAKE MECHANISM FOR RAILWAY-CARS.

SPECIFICATION forming part of Letters Patent No. 700,818, dated May 27, 1902.

Original application filed February 9, 1901, Serial No. 46,654. Divided and this application filed October 3, 1901. Serial No. 77,398. (No model.)

To all whom it may concern:

Be it known that I, CHARLES W. POWELL, a citizen of the United States, residing at Green Island, county of Albany, and State of New York, have invented certain new and useful Improvements in Brake Mechanism for Railway-Cars, of which the following is a specification.

The invention relates to such improvements; and it consists of the novel construction and combination of parts hereinafter described and subsequently claimed.

Reference may be had to the accompanying drawings, and the reference characters marked thereon, which form a part of this specification.

Similar characters refer to similar parts in both figures.

Figure 1 of the drawings is a view in side elevation of a truck-frame provided with my improved brake mechanism. Fig. 2 is a top plan view illustrating the arrangement of the brakes and brake-operating levers and connections, the truck-frame being omitted.

This application is a division of an application filed heretofore by me February 9, 1901, No. 46,654, for improvements in car-trucks.

The present invention relates more particularly to brake mechanism adapted for use upon electric-car trucks.

1 represents the truck-frame, which may be of any known form, no claim being made herein to the particular form of frame herein shown, which is particularly shown, described, and claimed in the said prior application, of which this is a division. The truck-frame is mounted upon and supported by the axles 2, upon which are fixed the wheels 3 in the usual manner. The brake-shoes 30 are mounted upon the brake-beams 31, one at each end of the truck outside the wheels. The brake-beams are suspended by links 32 from the wheel-supported frame of the truck in the usual manner. Each brake-beam carries a pair of levers 33, pivoted at their outer end on said beam near its outer ends and having their inner ends pivoted together at 34. These levers 33 are connected by rods 35, each with a corresponding lever on the same side on the opposite end of the truck. The lever 36 is pivoted at one end to the middle of the

brake-beam at 37 and provided at its other end with means for connecting the same with the brake-operating shaft, as the link 38, which may connect with a chain leading to 55 said shaft, said chain and shaft being omitted from the drawings. An intermediate portion of the lever 36 is connected by link 39 with an extension 40 of one of the levers 33.

From an inspection of Fig. 2 it will be seen that a pulling force exerted upon the link 38 at either end of the car will operate to produce a pull in the same direction upon the rods 35, which rods acting as a resistance will cause the levers 33 to force the brake-beam 65 and brake-shoes toward the wheels at that end of the truck. At the same time the pull exerted upon the rods 35 will be transmitted to the levers 33 at the other end of the car to cause the brake beam and shoes thereat to 70 be also drawn toward the wheels.

It will be seen that the levers are so arranged and connected that when those at one end of the truck are operated by the pull of the rods 35 the lever 36 at such end is drawn 75 inwardly against the brake-beam, which arrests its movement, whereupon said lever, beam, and neighboring levers 33 become practically a rigid construction.

The system of levers at one end of the 80 truck may be omitted and the system at the other end operated by connecting the rods 35 with any stationary support to serve as a resistance.

My invention, although particularly adapted for railway-cars, is applicable to various styles of vehicles.

What I claim as new, and desire to secure by Letters Patent, is—

1. In a brake mechanism for vehicles, the 90 combination with the truck-frame and a pair of wheels provided with bearings in said frame; of brake-shoes engageable with said wheels respectively; a shoe-supporting brake-beam movably supported on said frame; a 95 pair of levers severally pivoted at their outer ends upon the outer ends of said brake-beam and having their inner ends pivotally connected together, and their intermediate portions connected with a resisting medium; a 100 brake-operating lever pivoted at one end to the middle of the brake-beam; and a link

connecting said operating-lever with one of the levers of said pair, substantially as described.

2. In a brake mechanism for vehicles, the combination with the truck-frame; and axles and wheels provided with bearings in said frame; of brake mechanism at each end of the truck comprising brake-shoes engageable with the wheels at such ends respectively, a shoe-supporting brake-beam movably supported on said frame, a pair of levers severally pivoted at their outer ends upon the outer ends of said brake-beam and having their inner ends pivotally connected together,

a brake-operating lever pivoted at one end 15 to the middle of the brake-beam; and a link connecting said operating-lever with one of the levers of said pair; and links connecting each of the levers of said pair with its corresponding lever on the same side at the opposite end of the truck, substantially as described.

In testimony whereof I have hereunto set my hand this 2d day of October, 1901.

CHARLES W. POWELL.
